UNITED STATES PATENT OFFICE.

WILLIAM H. TOMEY, OF WALLINGFORD, CONNECTICUT, ASSIGNOR TO THE R. WALLACE & SONS MANUFACTURING COMPANY, OF SAME PLACE.

DESIGN FOR A METAL BORDER.

SPECIFICATION forming part of Design No. 22,485, dated May 30, 1893.

Application filed April 24, 1893. Serial No. 471,701. Term of patent 3½ years.

To all whom it may concern:

Be it known that I, WILLIAM H. TOMEY, of Wallingford, in the county of New Haven and State of Connecticut, have invented a new 5 Design for a Metal Border; and I do hereby declare the following, when taken in connection with accompanying drawing and the letters of reference marked thereon, to be a full, clear, and exact description of the same, and 10 which said drawing constitutes part of this specification, and represents a face view.

This invention relates to a design for a metal border, and the design consists in the configuration and ornamentation of the border as 15 hereinafter described and shown in the accompanying illustration.

The design consists of a series of corresponding, simple volute scrolls A, arranged side by side, with their uncoiled ends tangentially disposed with reference to a band B, forming the 20 upper edge of the border, below which they

are depressed, and with their coiled ends lifted in bold relief above the lower edge C, of the border. Interposed between the uncoiled ends of the scrolls, and emerging from the inner edge of the band B, a series of corresponding stem-like objects is arranged, which gives character to the upper portion of the border. More nearly in the center of the border, and closely adjacent to the coiled ends of the 25 scrolls, are located very small ribs E, which break the spaces between the scrolls.

I claim—

The design for a metal border as herein shown and described. 35

In testimony whereof I have signed this specification in the presence of two subscribing witnesses.

WILLIAM H. TOMEY.
